UNITED STATES PATENT OFFICE.

ALBERT V. GUDE, JR., OF ATLANTA, GEORGIA.

FLOOR OR WALL GROUND.

1,264,787.

Specification of Letters Patent. Patented Apr. 30, 1918.

Application filed October 9, 1916. Serial No. 124,608.

To all whom it may concern:

Be it known that I, ALBERT V. GUDE, Jr., a citizen of the United States, residing at Atlanta, in the county of Fulton and State 5 of Georgia, have invented new and useful Improvements in Floor or Wall Grounds, of which the following is a specification.

This invention relates to improvements in floor or wall grounds for the attachment of 10 finishing material such as furring, trim, molding, carpet strips and floor screeds to structural material such as brick or stone masonry walls, gypsum, claypipe, plaster board, marble, concrete, metal lathing, slate 15 or other structural material.

The principal objects of the invention are to provide a floor or wall ground which may be fastened and alined easily, quickly, and with the utmost security to the structural 20 material; which shall meet the necessities of all structural complications attendant upon modern methods of construction; which shall provide for certainty in the alinement and level and stability in the application 25 and adjustment of the finishing materials and shall entirely prevent injury to the structural material; which shall be of exceedingly simple and inexpensive construction; and which may be quickly made in a 30 thoroughly practical manner from pieces of wood and metal ordinarily cast aside as waste in the course of building operations.

With the above objects in view, the invention consists in certain features of structure 35 and combination which will appear in detail as the description proceeds, reference being had therein to the accompanying drawings, in which:

Figure 1 is an elevation, partly broken 40 away and in section, illustrating the invention as used in connection with a brick wall for the attachment of window trim.

Figs. 2, 3, and 4, are sectional views illustrating steps in the construction and attach- 45 ment of the improved ground.

Fig. 5 is a detail perspective view of a preferred form of nail-receiving element of the fastening ground.

Fig. 6 is an elevation showing the use of 50 scrap material, such as metal lathing and

wood blocks, for certain elements of the invention.

Figs. 7 and 8 are sectional views on the lines 7—7 and 8—8, respectively, of Fig. 6.

Fig. 9 is an elevation showing a strip of 55 herring-bone metal lathing as one of the structural elements of the ground.

Similar characters of reference designate 60 corresponding parts throughout the several views.

The invention is not limited to use with any specific wall structure, but proposes to meet and overcome the nail impenetrable structures now commonly employed in building operations by providing for the 65 application thereto of a nail-receiving block or strip for the securement, in a positive manner and in accurately alined relation, of window frames, door frames, trim, molding, carpet strips, floor screeds and the like 70 at different points as found necessary or desirable. By way of example Figs. 1 to 4 show the invention as used in connection with a brick wall 5.

The improved fastening ground consists 75 generally of a nail-receiving element 6, preferably a block or strip of wood and which for convenience is hereafter referred to as a "block", a metallic keying or anchoring element 7 which adjoins the inner face of 80 the block 6 and is suitably secured thereto and a hard-setting adhesive medium 9 by which the block 6 is securely fastened to the wall. The element 7 is essentially of skeleton or open fabric form whereby it is em- 85 bedded throughout its extent in the adhesive material and hence is securely gripped at all points by said material and whereby the adhesive material also has gripping engagement with the substantially entire overlying inner face of the block 6 and preferably with the sides or sides and ends thereof.

As shown and preferred the keying element 7 is composed of wire mesh which term is to be understood as generically including various similar foraminous materials such as wire gauze, metallic lathing, expanded metal or herring-bone metallic lathing. As 95 constructed of wire mesh the element 7 is secured against the inner face of the block 100

6 by nails or other headed fastenings; and said element is preferably, and as shown, of greater area than the block whereby it will project beyond the sides or sides and ends 5 of the block. The adhesive medium 9 may be of any suitable plastic cementitious material, plaster of Paris being preferred. Such material is applied in sufficient quantity to the preliminarily connected elements 10 6 and 7 to spread over and securely engage a considerable surface of the wall; and the block 6 is pressed against the adhesive material while the element 7, pressed into the material by the block 6, becomes substantially wholly embedded therein. In this 15 way the block 6 is directly anchored in and positively keyed to the plastic material and hence is secured with the utmost strength.

Fig. 2 shows the keying element 7 and the 20 block 6 as preliminarily connected by the fastenings 8; and Fig. 3 shows the application of the ground to the wall 5. The block 6, in a preferred form as shown by Figs. 1 to 5, is formed in its inner face with the 25 groove 10 and in its sides with grooves 11 to provide key seats, the adhesive material 9 being forced through the meshes or open spaces of the element 7 into the groove 10. In these figures the element 7 is illustrated 30 as a strip of wire gauze of suitable mesh, the heads of the nails 8 being large enough to engage the intersecting components of the gauze.

As shown by Figs. 6 to 8 inclusive, a scrap 35 piece of metallic lathing 12 is used as the keying element and an ordinary block 13 of wood is used as the nail-receiving element, said block being secured to the lathing 12 by staples 14 or other suitable fastening devices.

Fig. 9 shows a scrap piece of herring-bone 40 metallic lathing 18 connected in any suitable manner to an ordinary wood block 19 as a further variation of the improved ground.

It is obvious that other forms of metallic 45 keying elements having the characteristics of the invention may be employed if desired.

In the construction of the improved grounds it is possible and preferable to use 50 scrap or waste material usually cast aside in the course of building operations; and thereby a substantial economy in the intrinsic cost of the grounds and a further economy in their construction *in situ* may 55 be effected.

The grounds, constructed as described, are 60 pressed against the wall at appropriate intervals and locations after which the usual plastic or cement coating is applied to the 65 wall and over the portions of the ground which project beyond the block 6, the said coating and blocks being flush. The grounds are now ready for the attachment by nails in the usual manner of the finishing material

or trim. By way of example Fig. 1 shows 65 the grounds as carrying or supporting the frame members 15 and 16 of a door or window opening, and a base board 17.

I claim as my invention:

1. As an article of manufacture, a floor or 70 wall ground comprising a nail-receiving block, a metallic keying means in the form of a mesh member secured to said block adjacent its under face, and a mass of adhesive wall-engaging material adjacent the under 75 face of the block and against which the block is pressed, said material being forced through the open spaces of the mesh member into engagement with the under face of said block and also engaging and gripping 80 the strands or webs of said mesh member.

2. As an article of manufacture, a floor or 85 wall ground comprising a nail-receiving block, a metallic keying means in the form of a mesh member secured to said block adjacent its under face, said member being of greater area than said block whereby to project beyond the sides or sides and ends of 90 said block, and a mass of adhesive wall-engaging material adjacent the under face of the block and against which the block is pressed, said material being forced through the open spaces of the mesh member into engagement with the under face of said block and also engaging and gripping 95 the strands or webs of said mesh member.

3. As an article of manufacture, a floor or 100 wall ground comprising a nail-receiving block having its under face grooved, a metallic keying means of skeleton construction secured to said block adjacent its under face and over said groove and a mass of adhesive wall-engaging material adjacent the under 105 face of the block and against which the block is pressed, said material being forced through the open spaces of the keying means into the groove and into engagement with said block and also engaging and gripping the strands or webs of said keying means.

4. As an article of manufacture, a floor 110 or wall ground comprising a nail-receiving block, a mass of adhesive material against which said block is pressed, and a metallic keying means of foraminous structure secured to said block adjacent its under face 115 and having its strands or webs related to said blocks whereby said adhesive material when forced through the open spaces of said keying means into engagement with the under face of said block will also engage over 120 and grip the strands or webs of said keying means.

5. As an article of manufacture a floor 125 or wall ground including a nail-receiving block and a metallic keying means in the form of a mesh member located adjacent the under face of said block and secured thereto whereby said block with the keying

means attached may be pressed against adhesive wall-engaging material and said material may be forced through the open spaces of the mesh member to engage with the under face of said block and to engage and grip the strands or webs of said member.

In testimony whereof I have hereunto set

my hand in presence of two subscribing witnesses.

ALBERT V. GUDE, JR.
